Mots Law, PLLC(57) **CLAIM**

The ornamental design for an electroluminescence module, as shown and described.

DESCRIPTION

FIG. 1 is a front perspective view of an electroluminescence module;

FIG. 2 is a front view thereof;

FIG. 3 is a right side view thereof;

FIG. 4 is a top plan view thereof;

FIG. 5 is a rear view thereof; and,

FIG. 6 is a bottom plan view thereof.

A left side view of the electroluminescence module is a mirror image of the right side view, and therefore omitted.

The portions of the article in broken lines are shown for illustrative purposes only and form no part of the claimed design.

The long dash short dash line forms the boundary of the claimed design and forms no part of the claimed design.
